UNITED STATES PATENT OFFICE.

NILS F. OLSON, OF CHICAGO, ILLINOIS.

TEMPORARY BINDER.

1,111,173.

Specification of Letters Patent. Patented Sept. 22, 1914.

Application filed May 29, 1913. Serial No. 770,590.

To all whom it may concern:

Be it known that I, NILS F. OLSON, a resident of Chicago, in the county of Cook and State of Illinois, have invented certain new and useful Improvements in Temporary Binders, of which the following is a full, clear, and exact description.

The invention relates to temporary binders for pamphlets, papers, and magazines or booklets.

The invention designs to provide an improved device for temporary binding or covering papers or booklets, which will securely hold the papers or booklets in the cover. As heretofore constructed in binders, in which a removable bar has been used to secure the book in the binder, there has been no connection between the central portion of the bar and the back of the binder, and nothing to pass through the back of the papers or booklet to effectively secure them.

One object of the invention is to provide an improved binder in which the holding-bar is medially attached to the back as well as removably connected to the top and bottom of the binder, so that a book may be securely attached to a cover; the invention also designs to provide a device which extends through the back of the booklet or through the fold of the sheets, to securely hold them in the covers.

The invention also designs to provide a temporary binder of improved construction.

The invention consists in the several novel features hereinafter set forth and more particularly defined by claims, at the conclusion hereof.

In the drawings; Figure 1 is a perspective of a binder embodying the invention, the holder-bar being shown in operative position by full lines and shown in position assumed when the booklet is to be removed from or attached to the binder by dotted lines. Fig. 2 is a section taken on line 2—2 of Fig. 1. Fig. 3 is a section taken on line 3—3 of Fig. 1. Fig. 4 is a section taken on line 4—4 of Fig. 1. Fig. 5 is a detail section illustrating the manner of placing a pamphlet in the binder.

The improved binder comprises a cover consisting of sides *a* connected by a flexible back *b*, which may be of any suitable or usual construction. A strip *c* of flat metal extends from the top to the bottom of the back and is secured thereto by rivets or fasteners *c*². The ends of strip *c*, are bent at

right angles thereto, as at *c*', to serve as holding-means for the terminals of a holding-device *d*. The holding-device *d* comprises two bars *d*', which are pivotally connected to the center of the strip *c*, by a pin *d*² in a lug *d*³ which is rigidly secured to said strip. These bars *d*' are pivoted so they may be swung at right angles to the strip *c* as shown in Fig. 5, and so their outer terminals can be swung into slots *c*⁴ formed in the ends *c*' of strip *c*. The bars are formed of strips of thin flat metal and are slightly flexible. Each slot *c*⁴ has an off-set or catch portion *c*⁵ which is adapted to lock one of the bar-terminals therein. These bars may be twisted slightly to release them from the slots or catches *c*⁵ and their inherent resiliency holds each in place in the slots and against withdrawal, except when the bars are twisted.

An important attribute of the invention is that when the bars *d*' are swung into position indicated in dotted lines, their ends may be pushed or forced through the back 89 of magazine or book through the folds in a series of sheets as shown in Fig. 5. The thin ends of the bars facilitate passage through the paper or binding and then the book may be forced downwardly until its 85 back abuts against the strip *c*. Then the bars will be swung downwardly and their ends locked in the lugs *c*¹. An advantage in this construction is that the central portion of the holder-bar is securely attached 90 to the back of the binder. Furthermore, by forcing the bars through the back of the booklet and then forcing the booklet down to a position between the bars and the back-strip *c*, after which the bars are swung down 95 to engage the lugs *c*¹, the binding at the back of the pamphlet or the tear in the paper if the bar is forced through the paper, will serve to hold the paper or booklet against up and down movement relatively to the 100 back. Both bars may be forced through the booklet together.

The invention is not to be understood as restricted to the details set forth since these may be modified within the scope of the appended claims without departing from the spirit and scope of the invention.

Having thus described the invention what I claim as new and desire to secure by Letters Patent, is:

1. A temporary binder comprising a back, and a holding device comprising a plurality

- of bars, means for removably securing the outer ends of the bars to the back, and means for securing the bars to the back between the ends thereof, said bars being disposed to 5 pass transversely through the back of a book in the folds of sheets to be held.
2. A temporary binder comprising a back strip, a pair of bars, means for removably securing the outer ends of the bars to the 10 back-strip and means for securing the bars to the strip between the ends, and adapted to pass through the book or papers to be held.
3. A temporary binder comprising a back-strip, a bar pivotally connected at one end to 15 an intermediate portion of the back-strip, means for removably connecting the other end of the bar to the back-strip, the bar being adapted and disposed to pass transversely through the back of the book or the 20 fold in the papers to be held.
4. A temporary binder comprising a back-strip, a plurality of bars each pivotally connected at one end to an intermediate portion of the back-strip, means at the other ends of 25 the bars for removably connecting them to said back-strip, said bars being formed and disposed to pass transversely through the back of a book or the folds of sheets to be held.
- 30 5. A temporary binder comprising a combination of a back-strip, and a bar pivoted to the back-strip near the center thereof, the strip being bent at an angle at one end, and provided with means for locking one end of 35 the bar.
6. A temporary binder comprising a combination of a back-strip, a pair of bars, a lug to which each bar is pivoted near the center of the strip, means at the outer ends 40 of the back-strip for removably holding the ends of said bars.
7. A temporary binder comprising a back, and a holding device comprising bars, means for removably connecting the outer ends of 45 the bars to the back, and means for pivotally securing the bars to the back between the ends thereof.
8. A temporary binder comprising a back-strip, a bar pivotally connected at one end 50 to the central portion of the back-strip, means for removably connecting the other

end of the bar to the end of the back-strip, the bar being adapted and disposed to pass transversely through the back of the book or the fold in the paper to be held.

55

9. A temporary binder comprising a back-strip, a plurality of bars, each pivotally connected at one end to the central portion of the back-strip, means for removably connecting the other ends of the bars to the ends of 60 said back-strip, said bars being formed and disposed to pass transversely through the back of a book or the folds of the sheets to be held.

60

10. A temporary binder comprising a 65 combination of a back-strip, a bar pivoted to the back-strip near the center thereof, the strip being bent at an angle at one end and provided with means comprising a slot for locking one end of the bar.

70

11. A temporary binder comprising a combination of a back-strip, a bar pivoted to the back-strip near the center thereof, the strip being bent at an angle at one end and provided with means comprising a slot having an offset portion for locking one end of the bar.

75

12. A temporary binder comprising a combination of a back-strip, a pair of bars, a lug secured to the back-strip near the center thereof, said bars being pivotally secured to the lug, the back-strip being bent up at its ends, each of said ends having means comprising a slot having an offset portion in which the outer ends of one of the bars is adapted to rest and be locked in place.

80

13. A temporary binder comprising a combination of a back strip, a pair of bars, a lug secured to the back-strip near the center thereof, said bars being pivotally secured to the lug on either side thereof, the back-strip being bent up at its ends, each of 90 said ends having means comprising a downwardly extending slot having an offset portion in which the outer end of one of the bars is adapted to rest and be locked therein.
